UNITED STATES PATENT OFFICE

2,478,561

DEVICE FOR CREATING VACUUMS

Harry M. Berner, Chicago, Ill., assignor to American Hospital Supply Corporation, Chicago, Ill., a corporation of Illinois

Application June 28, 1943, Serial No. 492,623

2 Claims. (Cl. 251—104)

1

This invention relates to a device for creating vacuum, and more particularly to a device for creating vacuum without the use of a mechanical pump, a vacuum being created by the gravity flow of fluid from one container to another.

An object of the invention is to provide a device in which the flow of fluid from one container to another is used to create a vacuum. Another object is to provide in a device for creating vacuum by the gravity flow of fluid to containers between which the fluid may flow and which are reversible or interchangeable as to position so as to reverse the flow of fluid when desired. Yet another object is to provide a device in which fluid flowing from one container to another may be reversed in its flow without changing the construction or arrangement of the containers or the device.

Another object of the invention is to provide a valve for controlling the flow of fluid between a plurality of containers so as to control the quantity and speed of flow of material drawn into the vacuum inlet. A further object is to provide in a device in which a vacuum is created by the flow of fluid from one container to another, a valve for providing for the reversal of the flow of fluid when the positions of the containers are interchanged. Yet another object is to provide a valve for connecting the medium evacuated with the source of vacuum in either position of the containers and without regard to the direction of the flow of fluid therebetween.

Other features and advantages will appear from the following specification and drawings, in which—

Fig. 1 is a side elevational view of a device embodying the invention; Fig. 2 is a front elevational view of the same device; Fig. 3 is a side view partly in vertical section showing the construction and arrangement of the valve and conduits; Fig. 4 is an enlarged detail elevational view of the bracket which engages the valve casing; Fig. 5 is a side elevational view of a modified form of the device; Fig. 6 is a front elevational view of the same modified form of the device; Fig. 7 is a plan view of the base of the embodiment of the device shown in Figs. 4 and 5; Fig. 8 is a fragmentary detail vertical sectional view showing the valve construction; and Fig. 9 is a transverse sectional view taken along the line 9—9 of Fig. 8.

The present invention contemplates a device in which a vacuum is created by the flow of fluid between two or more containers. In the device, at least a pair of containers are disposed in vertically-spaced relation and the fluid flows from

2

the upper container to the lower container and creates a vacuum in the upper portion of the upper container. A conduit communicates with this upper portion of the upper container and is connected to the medium to be evacuated. In the device, the containers and the valve therebetween are so arranged that the containers may be reversed or interchanged in position, and the flow of fluid may thereupon be reversed without interrupting the vacuum for any substantial period of time.

In the embodiment of the invention shown in Figs. 1 to 3, a base 10, including a plurality of struts or members 11, 12 and 13 which may be equipped with rollers 14 at their ends, provides a central mounting 15 which supports an upwardly-extending standard 16. The standard 16, in turn, is equipped with a shaft 17 which pivotally supports the frame 18.

At the ends of the frame 18 are brackets 19 and 20 which are equipped with shafts 21 and 22, respectively, received within the tubular ends of the frame 18. Set screws 23 and 24 provide for the locking of the shafts 21 and 22 respectively in position and for the adjustment of these shafts. The bracket 19 supports a container 25. A ring 26 supported by the frame 18 extends about the neck 27 of the container 25 and engages the same. A ring 28, carried by the frame 18, engages the neck 29 of a container 30 and, with the bracket 20, supports the same.

As seen particularly in the fragmentary view of Fig. 3, the container 25 is equipped with a closure member or cap 31 which may threadedly engage the neck of the container or may be otherwise suitably secured to the container to close the open neck thereof. The closure 31 is equipped with a plurality of tubes 32, 33 and 34 extending therewith. The tubes 32, 33 and 34 extend through the closure and through the washer 31a within the closure. If desired, a rubber band 35 or other suitable means may extend about the tubes, as indicated.

The tubes 32 and 33, as seen in Figs. 1, 2 and 3, are relatively long tubes which extend into the container and terminate adjacent the bottom of the container opposite the neck thereof. These tubes are inlet tubes. The tube 34, on the other hand, is an outlet tube and is relatively short, terminating within the container immediately adjacent the neck thereof and the closure 31.

The tube 34 is preferably provided with a longitudinal slot in the end thereof. With this slot in the end of the tube, if a few drops of liquid

fall into the tube, they will not interfere with the passage of air therethrough since the liquid collects at the lower end of the tube and the air may pass through the slot at a portion of the tube slightly above the end thereof.

A similar closure 36, inlet tubes 37 and 38, and an outlet tube 39 are provided for the container 30. Since the construction of the closure and inlet and outlet tubes for the two containers are substantially identical, these members will not be described in detail in connection with the container 30.

A valve 40 is provided with a casing 41 and a plug 42 therein. Preferably, the casing is tapered on the inner side thereof, and the valve plug 42 is equipped with a compensating taper so that the plug fits snugly within the casing. A spring 43, supported against an end plate 44, urges the plug into snug engagement with the inner surface of the casing. The casing 41 may be mounted on the supporting bracket 45 carried by the frame 18, while the plug 42 is equipped with an extending portion 46 which is secured to the shaft 17 which provides a pivotal mounting for the frame 18. Thus, the casing 41 is rotatable with the frame 18, while the plug 42 is fixed in position by attachment to the shaft 17.

As seen particularly in Figs. 3 and 4, the casing 41 may be equipped at its end with a pair of pins 105 and 106 which extend into a longitudinal slot 107 in the bracket 45. The pins are slightly smaller than the width of the slot so as to allow a slight play of the casing 41 with respect to the bracket 45. At the same time, the pins engage the walls of the slot when the casing is moved so that the casing may not be moved any substantial distance without moving the bracket 45. Similarly, when the frame 18 carrying the bracket 45 is rotated, the casing is also rotated by reason of the engagement of the bracket with the pins 105 and 106.

The casing 41 may be equipped with a pair of inlet ports 47 and 48, equipped respectively with tubes 49 and 50 communicating with the conduits 51 and 52 which, in turn, are connected respectively to the inlets 37 and 38 for the container 30. Immediately adjacent the inlet ports 47 and 48 is an outlet port 53 provided with a tube 54 connected to a conduit 55 communicating with the outlet tube 39 for the container 30. The inlets 47 and 48 and outlet 53 are preferably on the same side of the casing 41 and in longitudinal alignment with each other.

The lower side of the casing 41 may be equipped with inlets 56 and 57 which communicate with the inlets 32 and 33 for the container 25 and with an outlet 58 which communicates with the outlet 34 for the container 25. The tube 59 connected to the outlet port 58 may be provided with a manually-operable valve 60 for controlling the flow of fluid or air through the tube 59.

The plug 42 is provided with a transverse groove 61 extending thereabout, the passage being adapted to communicate at its upper end with the outlet 53 or with the outlet 58, and at its lower end with the inlet 48 or the inlet 57. A passage 62 in the plug 42 is adapted to communicate at one end with the inlet 47 or the inlet 56, and at its other end with a tube 63 leading to the medium to be evacuated. A passage 64 in the plug 42 serves as an outlet passage and may communicate selectively with the outlet 58 or the outlet 53. When the outlet 58 is in lower position, as indicated in Fig. 3 of the drawing, this outlet serves as an air exhaust, while when it is

in upper position it serves as a liquid outlet. Similarly, when the outlet 53 is in upper position, as indicated in Fig. 3, it serves as a liquid outlet, while when in lower position in place of the outlet 58 the outlet 53 serves as an air exhaust.

The tube 63 is connected to a conduit 65 which leads to a container 66 which serves as a trap for the material which is evacuated and passes through the conduit 70. The container 66 is provided with a closure 67 and a pair of tubes 68 and 69, the tube 68 leading to a conduit 70 which may be connected to the medium to be evacuated.

The conduits may be of rubber or other suitable material, while the base, frame, valve and the like are preferably of metal. The containers may be of glass. If the device is to be used for therapeutic purposes, brass, stainless steel or monel metal may be used for the parts which come in contact with the fluid.

In operation, one of the containers is filled with liquid, and this container is placed in upper position by rotating the frame 18 about the shaft 17. A stop 71 carried by the standard 16, engages the frame when the upper container is in the desired vertical position.

The fluid in the container 30 in upper position flows downwardly through the outlet 39, conduit 55, through the port 53, and the casing 41, then through the transverse passage 61 in the plug 42, and into the inlet port 57. From the inlet port 57, the fluid flows to the inlet 33 in the container 25. The flow of fluid from the container 30 creates a vacuum within the inlet tube 37 and tends to draw air into the container 30 through the inlet tube 37, conduit 51, inlet port 47, and passage 62 in the valve 40. The passage 62 communicates with the tube 63, conduit 65, container 66, and conduit 70, and serves to create a vacuum in the medium which is to be evacuated. The inlet tube 38 is closed off by the surface of the plug 42 engaging the inlet port 56.

As the fluid flows into the container 25 in lower position, the air in the container passes upwardly and outwardly through the inlet 34, through the valve 60, outlet port 58 and exhaust passage 64. Manual control of the valve 60 serves to control the flow of air from the container 25 and thus controls the flow of fluid from the upper container to the lower when the valve 60 is in the position shown in Fig. 3. In upper position, on the other hand, the valve 60 controls the flow of liquid from the upper container to the lower container.

The inlet 32 is closed by the surface of the plug 42 in engaging with the inlet port 56.

When the liquid in the container 30 has been transferred to the container 25, the frame 18 is rotated about the shaft 17 to reverse the positions of the containers. In the new position, the container 25 is in upper position and the container 30 in lower position. In this changed position, the outlet 34 of the container 25 communicates through the passage 61 with the inlet 38 in the container 30 to permit fluid to flow from the container 25 to the container 30. The inlet 32 of the container 25 communicates with the passage 62 in the valve 40 and through this passage with the medium to be evacuated. The outlet 39 of the container 30 communicates with the exhaust passage 64. As the fluid flows from the container 25 to the container 30, a vacuum is drawn through the conduit 70 and the air, which is forced from the container 30, passes out through the exhaust passage 64.

In the continued operation of the device, when

the liquid has passed from the upper container to the lower container, the positions of the containers are reversed and the operation continues.

In the modified form of the invention shown in Figs. 4, 5, 6, 7 and 8, a base 80 is equipped with a pair of legs 81 and 82 and a mounting 83 supporting a standard 84. The standard 84, in turn, supports a shaft 85 on which is pivotally mounted a frame 86 for supporting two pairs of containers, the upper pair being indicated at 87 and 88 and the lower pair at 89 and 90.

Each of the containers 87, 88, 89 and 90 may be substantially the same in construction as the containers 25 and 30 shown in the embodiment of the invention described in connection with Figs. 1 to 3.

The conduits communicating with the containers 87, 88, 89 and 90 are the same as those described in connection with the embodiment of the invention shown in Figs. 1 to 3 and communicate with a valve 91. The valve 91 includes a casing 92 and a plug 93, as in the principal embodiment of the invention. The valve construction is similar to that in the principal embodiment of the invention except that each of the ports is divided and equipped with a pair of tubes. As seen in Fig. 8, the port 93, for example, receives a pair of tubes 94 and 95, the tubes 94 and 95 connecting respectively to conduits 96 and 97. Thus, each of the ports in the valve corresponding to the ports in the principal embodiment of the invention communicates with a pair of tubes within the pair of adjacent containers.

The conduits 98 and 99 which connect to the outlet tubes of the containers 89 and 90 are joined at the manually-controlled valve 100. From this valve, a tube 101 communicates with the exhaust passage 102 in the valve.

In other respects, the construction of the embodiment of the invention shown in Figs. 4 to 8 inclusive is substantially similar to the principal embodiment of the invention. In operation, the embodiment shown in Figs. 4 to 8 is similar to that shown in Figs. 1 to 3, except that in each case the fluid flows from the two containers in upper position to the two containers in lower position. Since all of the fluid flows through the valve 91, the quantities in each pair of containers will be balanced.

Although the invention has been described in connection with specific embodiments, it will be apparent that modifications and changes may be made without departing from the spirit and scope of the invention.

I claim:

1. In an evacuating device, a valve mechanism comprising a casing equipped with an outlet port and a pair of inlet ports on one side

thereof and with an outlet port and a pair of inlet ports on the other side thereof, and a plug rotatably supported within said casing and equipped with a passage extending transversely thereabout, said outlet ports being in alignment in the plane of said rotation whereby either of said ports may be selectively brought into communication with one end of the passage in said plug, a pair of said inlet ports being in alignment in the plane of rotation whereby one of said pair of inlet ports may be brought into communication with the other end of said passage in said plug, the other pair of inlet ports being in alignment in the plane of said rotation whereby one of said last-mentioned inlet ports may be brought into communication with a passage in said plug leading to the medium to be evacuated, an exhaust passage in said plug communicating selectively with the other of said outlet ports.

2. In an evacuating device, a valve mechanism comprising a casing equipped with an outlet and a pair of inlet ports and another outlet and another pair of inlet ports, and a plug within said casing equipped with a passage extending transversely thereabout and equipped also with an exhaust passage and a passage adapted to communicate with a medium to be evacuated, said casing and said plug being rotatable with respect to each other, said outlet ports being in alignment in the plane of rotation and adapted to be brought selectively into communication with one end of said transverse passage, two of said inlet ports consisting of one of each of said pairs being in alignment in the plane of rotation and being adapted to be selectively brought into communication with the other end of said transverse passage, the other two inlet ports being in alignment in the plane of rotation and adapted to be selectively brought into communication with said passage adapted to communicate with a medium to be evacuated, the other outlet port being in communication with said exhaust passage.

HARRY M. BERNER.
